(57) CLAIM

The ornamental design for a perfume bottle, as shown and described.

DESCRIPTION

FIG. 1 is a perspective view of a perfume bottle showing our new design;

FIG. 2 is a side elevation view thereof, the opposing side elevation view being identical;

FIG. 3 is a side elevation view thereof rotated 45 degrees, the opposing side elevation view being identical;

FIG. 4 is a top view thereof, shown at a reduced scale;

FIG. 5 is a perspective view of the cap portion of the perfume bottle;

FIG. 6 is a side elevation view thereof, the opposing side being identical;

FIG. 7 is a side elevation view thereof rotated 45 degrees, the opposing side elevation view being identical; and,

FIG. 8 is a top plan view thereof shown at an enlarged scale. The broken lines in the drawing for the surface shading illustrate the portions of the perfume bottle that form no part of the claimed design.
